UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

WORK-CLAMP.

1,197,639.

Specification of Letters Patent. Patented Sept. 12, 1916.

Application filed March 1, 1916. Serial No. 81,529.

To all whom it may concern:

Be it known that I JOHN KIEWICZ, a citizen of the United States, residing at Boston, county of Suffolk, State of Massachusetts, 5 have invented an Improvement in Work-Clamps, of which the following description, in connection with the accompanying drawing, is a specification, like characters on the drawing representing like parts.

10 This invention relates to work clamps for sewing machines and has for its object to provide a novel work clamp which is simple in its construction and positive and sure in its action, and which has other advantages, all as will be more fully hereinafter set forth.

15 While my improved work clamp is capable of use with sewing machines of various types, it is particularly applicable to sewing machines of the buttonhole type, and I have, therefore, shown it herein as it would be embodied in a buttonhole sewing machine.

20 I will first describe a selected embodiment of my invention and will then point out the novel features thereof in the appended claims.

25 Figure 1 is a side view of a portion of a buttonhole sewing machine equipped with my improved work clamp; Fig. 2 is a side view of the work clamp looking from the opposite side from that shown in Fig. 1 with the bearing for the shaft omitted; Fig. 3 is a front view; Fig. 4 is a top plan view of the work clamp removed from the machine; Fig. 30 5 is a section on the line 5—5, Fig. 7; Fig. 6 is a bottom view of the clamp plate; Fig. 7 is a section on the line 7—7, Fig. 5.

35 I have shown at 1 the portion of a buttonhole sewing machine frame provided with the head 2 in which reciprocates the needle bar 3 carrying the usual needle 4 and also provided with the bed plate 5 on which the work clamp is secured.

40 45 6 is the buttonhole cutter by which the buttonhole is cut either before or after the stitching operation.

The parts thus far described are or may be of any suitable or usual construction as they form no part of the present invention.

50 55 50 My improved work clamp comprises a

clamp plate 7 which is mounted on the bed frame 5 and which carries the work-clamping members between which the work is clamped. This clamp plate 7 is herein shown as mounted for reciprocating movement toward and from the front of the machine to give the work a feeding movement during the formation of the edge stitches at the side of the buttonhole, and is also capable of movement laterally so as to provide for barring stitches at the end of the buttonhole, and also so as to permit the stitches to be formed around the eye end of the buttonhole. The clamp plate is shown as slidably mounted in ways 8 formed in the bed frame 5 and is given its work-feeding movement by the feed cam 360 as usual in buttonhole sewing machines. This clamp plate 7 is provided with an opening 9 through which the stitching mechanism 70 operates.

55 60 65 70 75 80 85 90 95 100 The under work-clamping member comprises two members 10 and 11 in the form of plates or leaves that are situated at each side of the opening 9 and are provided with roughened upper work-engaging surfaces. The upper work-clamping members are shown at 12 and 13, respectively, they having any suitable or usual construction and being pivotally mounted on arms 14 and 15 which are arranged for vertical movement, as usual in work clamps, thereby providing for moving the upper work-clamping members 12 and 13 toward and from the under members 10 and 11. The arms 14 and 15 which sustain the upper members 12 and 13 are rigidly secured to blocks or heads 16 and 17 which are loosely pivoted on a rock-shaft 18 that is journaled in suitable bearings 19 carried by the clamp plate 7. These heads or blocks 16 and 17 are independent from each other and are independently pivoted on the rock-shaft 18. There is, however, a connection between said blocks so that when the head or block 17 is rocked in a direction to depress the arm 15, the other block 16 will be correspondingly operated, so that both of the upper work-clamping members 12 and 13 can be clamped against the work by turning the block 17

about the shaft 18. This connection is herein shown as a lip or extension 21 on the block 17 which is situated in front of the rock-shaft 18 and which overlies a portion 22 on the block 16. With this construction the turning of the block 17 in a direction to bring the clamping member 13 into work-clamping position will operate to give the block 16 a similar movement. The block 16 is acted upon by a spring 23 which is received in a recess 24 formed in the underside thereof and which operates to elevate the work clamp 12. The turning movement of the block 16 due to the spring 23 acts through the portions 22, 21 to raise the work-clamping element 13.

The under work-clamping members 10 and 11 are provided with heads 50 at their rear ends, each of which is formed with a recess or groove 51 in which the shaft 18 is received, as shown in Fig. 5. The heads or blocks 16 and 17 are provided on their under faces with grooves 52 in which the heads 50 are received. In this way the under clamping members are held in proper position relative to the upper clamping members. 53 are hold-down members that are secured to the clamp plate 7 and that overlie the shanks of the lower work-clamping members 10 and 11, as shown in Fig. 5, thereby assisting in holding them in proper position. These hold-down members 53 have associated therewith springs 54 which act against the under clamping members and tend to keep them in the position shown in Fig. 4, but permits said members to be separated slightly for the purpose of stretching the cloth after it is clamped, as is usual in buttonhole sewing machines. For thus separating or spreading the clamping members the blocks 16 and 17 are provided with lugs 540 which are acted upon by a suitable cam that tends to separate them slightly at the proper time to spread the cloth.

45 The block 17 is formed with an upwardly-directed arm 25 which is adapted to be engaged by an arm 26 fast on the rock-shaft 18 so that movement of the arm 26 toward the front of the machine will operate through the arm 25 to turn the block 17 and depress the work-clamping element 13 into work-clamping position, and because of the connection between the blocks 17 and 16, this movement is transmitted to the other 55 work-clamping element 12. The arm 25 is herein shown as provided with an adjusting screw 27 which has direct engagement with the arm 26, this screw being provided to effect any necessary adjustment of the parts 60 to accommodate work of different thickness.

Means are provided whereby the arm 26 will be operated either by hand or automatically by the machine. The hand mechanism comprises a lever 28 fast on a stud

29 which is journaled in an arm or bracket 30 rising from the clamp plate 7. This stud has thereon a head 31 provided with a cam surface 32 that is adapted to be brought against the back side of the arm 26 as the lever 28 is swung in the direction of the arrow, Fig. 2. By this means the swinging movement of the lever 28 will operate to move the arm 26 forwardly and thus depress the work-clamping elements 12 and 13. As stated above, means are also provided 75 for automatically operating the work clamps to clamp the work at the beginning of the stitching operation. For this purpose, I have provided an actuating lever 33 which is pivoted to the frame at 34 and is provided with a finger 35 that is adapted to engage the upper end 36 of the arm 26 as the lever 33 is rocked. This lever 33 may be actuated at the proper time by any suitable means which is operating in proper timed 85 relation with the other parts of the sewing machine. In the construction herein shown the lever 33 is actuated by a cam 350 which is mounted on a rotating element 360 which may be the usual feed cam of the sewing 90 machine by which the work is given its feeding movement, this cam 350 operating as it moves in the direction of the arrow, Fig. 1, against the lower end of the lever 33, thereby to turn said lever about its pivot in a 95 direction to carry the finger 35 against the arm 26. The cam 350 is so positioned on the element 360 that when the sewing machine is set in operation the lever 33 will be actuated to depress the work-clamping elements 12 and 13 against the work. The lever 33 is acted upon by a spring 37 which tends to return it to normal position after the cam 350 has passed from under the lower end of the lever 33. Means have also 100 been provided for locking the work-clamping elements closed against the work after they have been thus brought into work-clamping position and for releasing the locking element at the end of the stitching operation, thereby permitting the clamps to be raised from the work. For this purpose I have provided a locking latch 38 which is pivotally mounted at 39 on the bracket 30 and which is adapted to drop in behind the 115 shoulder 40 on the lever 26 when the latter has been moved forwardly into work-clamping position, as shown in Fig. 2. This locking latch 38 is acted upon by a spring 41 which automatically moves it into operative position when the lever 26 is moved forwardly. Means are also provided for automatically releasing the locking latch 38 at the end of the stitching operation. This is herein accomplished by providing the 120 locking latch with an arm 42 extending upwardly therefrom and which is provided with a cam projection 43 which is engaged

by a cam extension 44 on the lever 33 at the proper time in the cycle of operation. The engagement of the cam extension 44 with the cam projection 43 swings the arm 42 laterally thereby raising the latch 38.

When the machine is stopped at the end of the stitching operation, the parts come to rest in the position shown in Fig. 1. When the machine is started, the initial movement 10 of the member 360 will cause the cam 350 to operate the lever 33, thereby to cause the work-clamping members 12 and 13 to be depressed into operative engagement with the work, and as they are thus depressed the 15 locking latch 38 will automatically swing into engagement with the shoulder 40 and thus lock the work clamps closed, as stated above. After the work is thus clamped the stitch-forming mechanism is set in operation as usual in buttonhole sewing machines, and the clamp plate 7 with the work clamps thereon is given a feeding movement 20 to the right, Fig. 1, to feed the work, this feeding movement being derived from any 25 suitable mechanism, such, for instance, as the feed cam 360. During this feeding movement of the clamp plate the arm 42 with its cam projection 43 is carried away 30 from the end of the lever 33 and the cam 350 will preferably be so shaped as to hold the end of the lever depressed until after the work clamp has been moved forwardly sufficiently to carry the arm 42 clear of said lever. After the cam 350 has passed under the 35 lever 33, it will return to the position shown in Fig. 1. When the stitching on one side of the buttonhole has been completed, the clamp plate is given a reverse feeding movement toward the left, Fig. 1, to restore the 40 parts to the position shown in said figure. Just as the stitching on a buttonhole is completed, the cam projection 43 on the arm 42 comes into engagement with the cam extension 44 on the arm 33, thereby forcing the 45 arm 42 laterally and releasing the latch 38 from the shoulder 40. As soon as the latch is thus released from the shoulder 40, the spring 23 operates to raise the work clamp.

While I have illustrated herein a selected 50 embodiment of my invention, I do not wish to be limited to the constructional features shown.

I claim:

1. In a work clamp for sewing machines, 55 the combination with a clamp plate, of a rock-shaft journaled thereon, two work clamping members loosely and independently pivoted on said rock-shaft, means for turning the rock-shaft, a connection between said rock-shaft and one of the work-clamping members by which turning movement of said shaft depresses said work-clamping member into work-clamping position, and means to transmit such movement of the lat-

ter work-clamping member to the other 65 clamping member.

2. In a work clamp for sewing machines, the combination with a clamp plate, of a rock-shaft journaled thereon, two blocks loosely and independently pivoted on said rock-shaft, a work-clamping member carried by each block, means for turning the rock-shaft, a connection between said rock-shaft and one block by which turning movement of the rock-shaft depresses the work-clamping member carried by said block, and means to transmit such movement of said latter block to the other block.

3. In a work clamp for sewing machines, the combination with a clamp plate, of a 80 rock-shaft journaled thereon, two blocks pivotally but independently mounted on said rock-shaft, a work-clamping member carried by each block, a connection between the rock-shaft and one block by which turning movement of the rock-shaft depresses the corresponding work-clamping member into work-clamping position, said block having a portion overlapping the other block whereby the work-clamping movement of the first 90 block is transmitted to the other block.

4. In a work clamp for sewing machines, the combination with a clamp plate, of a rock-shaft journaled thereon, two work-clamping members loosely but independently 95 pivoted on said rock-shaft, an arm rigid with one of said work-clamping members, an arm fast on the rock-shaft and adapted to engage the first-named arm, means to actuate the arm of the rock-shaft thereby to 100 depress the last-named work-clamping member into work-clamping position, and means to transmit said work-clamping movement of said member to the other member.

5. In a work clamp for sewing machines, 105 the combination with a clamp plate, of a rock-shaft journaled thereon, two blocks loosely but independently pivoted on the rock-shaft, a work-clamping member carried by each block, an arm rigid with one block, 110 an arm fast on the rock-shaft and adapted to engage the first-named arm, means to actuate the arm on the rock-shaft thereby to depress one of the work-clamping members into work-clamping position, and means to 115 transmit the work-clamping movement of said member to the other work-clamping member.

6. In a work clamp for sewing machines, 120 the combination with a clamp plate, of a rock-shaft journaled thereon, two blocks loosely but independently pivoted on the rock-shaft, a work-clamping member carried by each block, one of said blocks having an extension overlying a portion of the other 125 block and also having an arm rigid therewith, an arm fast on the rock-shaft and adapted to engage the first-named arm, and

means to actuate the arm on the rock-shaft thereby to depress the work-clamping members into work-clamping position.

7. In a work clamp for sewing machines, 5 the combination with a clamp plate, of work-clamping members movably mounted thereon, a latch for holding the work-clamping members in work-clamping position, and a combined clamp-actuating and latch-releasing member adapted in one position to move the work-clamping members into work-clamping position and in another position to release the latch to unclamp the work-clamping members.
- 15 8. In a work clamp for sewing machines, the combination with a clamp plate, of a rock-shaft journaled thereon, two work-clamping members mounted on the rock-shaft, an arm fast on the rock-shaft by 20 which it may be turned thereby to depress the work-clamping members into work-clamping position, a latch for engaging said arm automatically thereby to lock the work clamp in work-engaging position, and a 25 combined clamp-actuating and latch-releasing member adapted in one position to engage the arm on the rock-shaft and carry the work clamps into work-clamping position and in another position to release the 30 latch so as to unlock the work-clamping member.

9. In a sewing machine, the combination with a frame, of a clamp plate movably mounted thereon, a rock-shaft journaled on 35 said clamp plate, work-clamping means mounted on the rock-shaft, an arm fast on the rock-shaft by which the latter may be turned to depress the work clamps into work-clamping position, a locking latch for engaging said arm to lock the work clamps in 40 work-clamping position, and a combined clamp-actuating and latch-releasing member movably mounted on the frame and adapted in one position to engage the arm on the 45 rock-shaft thereby to depress the work clamps into work-clamping position and in another position to engage the latch and release the work clamp.

10. In a sewing machine, the combination 50 with a frame carrying stitch-forming mechanism, of work-clamping means comprising movable work-clamping members, a cam member for moving the work-clamping means and frame relative to each other, a 55 clamp-actuating member operated by the cam member for moving the work-clamping members into work-clamping position, and a latch to hold said work-clamping members in such position, said clamp-actuating member 60 operating to release the latch during the relative movement between the work-clamping means and said frame.

11. In a sewing machine, the combination with a frame carrying stitch-forming mech-

anism, of work-clamping means comprising 65 movable work-clamping members, a cam member for moving the work-clamping means relative to said frame, a clamp-actuating member operated by said cam member for moving the work-clamping means into 70 work-clamping position, and a latch to hold said work-clamping members in such position, said clamp-actuating member operating to release the latch during the movement of the work-clamping means. 75

12. In a sewing machine, the combination with a frame carrying stitch-forming mechanism, of work-clamping means comprising movable work-clamping members, a cam member for moving the work-clamping 80 means and frame relative to each other, a lever pivoted to the frame and actuated by said cam member to move the work-clamping members into work-clamping position, and a latch to hold said work-clamping 85 members in such position, said lever being shaped to engage and release the latch during the relative movement of the work-clamping means and frame.

13. In a sewing machine, the combination 90 with a frame carrying stitch-forming mechanism, of a clamp plate, a rock-shaft journaled thereon, two work-clamping members loosely but independently pivoted on said rock shaft, a connection between said rock 95 shaft and one of the work-clamping members by which turning movement of said shaft depresses said work-clamping member into work-clamping position, means to transmit such movement of the latter work-clamping member to the other work-clamping member, a cam member for moving the clamp plate and frame relative to each other, and a lever pivoted to the frame and actuated by said cam member, said lever turning 100 the rock-shaft thereby to move the work-clamping members into operative position. 105

14. In a sewing machine, the combination with a frame carrying stitch-forming mechanism, of work-clamping means comprising 110 movable work-clamping members, a cam member for moving the work-clamping means and frame relative to each other first in one direction and then the other, a clamp-actuating member operated by the cam member 115 for moving the work-clamping members into work-clamping position, and a latch to hold said work-clamping members in such position, said clamp-actuating member operating to release the latch during the relative movement between the work-clamping means and frame in the latter direction. 120

15. In a sewing machine, the combination with a frame carrying stitch-forming mechanism, of work-clamping means comprising 125 movable work-clamping members, means to move the work-clamping means and frame relative to each other first in one direction

and then in another, a clamp-actuating member, means to operate said clamp-actuating member to clamp the work-clamping members against the work at the beginning 5 of the stitching operation, and a latch to hold said work-clamping members in their operative position, said clamp-actuating

member engaging and releasing the latch during said relative movement in the latter direction.

10

In testimony whereof I have signed my name to this specification.

JOHN KIEWICZ.
